COLLAPSIBLE CELLULAR CARTON

Hubert Velman Bolding, Jeffersonville, Ind., assignor to The Bradley & Gilbert Company,

Louisville, Ky., a corporation of Kentucky
Application June 24, 1948, Serial No. 34,952

4 Claims. (Cl. 229—28)

1

This invention relates to cartons which are partitioned or cellular in nature and adapted to the packaging of such articles as bottles, light bulbs, eggs, candy novelties, fruits, vegetables, cookies, etc.

An object of the invention is to so construct a single blank from sheet material that a cellular carton comprising walls, spaced partitions, and if desired a top or cover may be readily and quickly set up by automatic folding carton machinery at a high rate of speed, the carton being collapsible into flat form after being so set up to thereby facilitate storage, handling, and shipping.

Another object of the invention is to arrange the partitions which form the individual cells in such manner that they also function to strengthen certain portions of the carton, particularly the bottom, and rigidify the same from top to bottom, side to side, and end to end. As a result, when some units are removed from a loaded carton the partitions will not collapse in the empty cell and the remaining contents are as securely positioned as though the entire carton were filled.

Still a further object of the invention is to so construct the various components of the forming blank that, after the carton is partially set up, excepting only the partitions which form the cell-like pockets, the collapsed or flattened units may be readily withdrawn from stock and quickly and easily opened by slight pressure exerted on the ends of the collapsed carton and the partitions positioned properly, thus rendering the carton ready for immediate use.

It should be understood that the invention is not limited to the use of any particular material. While in many instances the use of so-called pasteboard will prove most satisfactory, substantially any material may be used which is obtainable in sheet form such as plastics, sheet metal, plastic impregnated fabrics or paper, laminate of cellophane, plastic sheeting, etc. Use of transparent plastic sheets possesses the advantage of providing a completely transparent partitioned plastic box particularly suitable for packaging articles where it is desirable to display different species of a product in a single display assembly.

Various other objects and meritorious features of the invention will become apparent from the drawings, wherein like numerals refer to like parts throughout the several figures, and wherein:

Fig. 1 is a plan view of the sheet material blank used in forming the carton;

Fig. 2 is a perspective illustrating an initial

2

stage in setting up the carton from the blank illustrated in Fig. 1;

Fig. 3 is a perspective illustrating a somewhat more advanced stage of formation;

Fig. 4 is a central transverse section through Fig. 3;

Fig. 5 is a perspective illustrating the initial step in disposing the partitions to form the interior cellular structure;

Fig. 6 is a section through 6—6 of Fig. 5;

Fig. 7 is a perspective illustrating a carton completely formed and set up ready for use;

Fig. 8 is a section through 8—8 of Fig. 7;

Fig. 9 is a perspective illustrating the carton closed and ready for shipment;

Fig. 10 is a section through 10—10 of Fig. 9, and

Fig. 11 is a bottom elevation of the carton collapsed for shipment or storage.

Referring now to Fig. 1, the blank formed from a single sheet of material is preferably die cut to form the contours shown and scored in locations to be described hereinafter for facilitating the setting up operation. The blank comprises side

walls 10 and 12 separated by score lines 11 and 13 from what may be designated a duplex end wall consisting of sections 14 and 14', the two components being identical in every way and joined by a score line 15 as illustrated. At the other

end of side wall 10 and separated therefrom by score line 17 is the other duplex end wall consisting of sections 16 and 16' divided by score line 19. Projecting beyond section 16' and separated therefrom by score line 21 is a tab 18, to

one side of which adhesive is applied for a purpose to be described hereinafter.

Projecting from one side of said wall 10 and separated therefrom by score line 23 is a wing comprising a bottom section 18 beyond which and separated therefrom by score line 25 is a longitudinal partition section 20. The outer margin of partition section 20 is die cut to provide locking tongues 22 and 24 separated by slots 26 and 28 from a central tongue 30.

A substantially identical wing separated by score line 27 from the corresponding side margin of end wall 12 is similarly provided with a bottom section 18', a longitudinal partition section 20', locking tongues 22' and 24', slots 26' and 28', and central tongue 30'.

Adhesive is spotted on tongues 22', 24' and 30' adjacent the outer free ends thereof and a band of adhesive 32 is applied across the partition section 20' adjacent to but spaced slightly from score line 29 which separates it from bottom section 18'.

Projecting beyond the other side margin of

side wall 12 and separated therefrom by score line 31 is a cover section 34 beyond which extend spaced-apart cover-positioning tabs 36 and 38 separated from section 34 by score lines.

Extending beyond the other side margin of side wall 10 is a top partition section comprising a central cover portion 40, on each side of which and separated by score lines 33 and 35 are transverse partitions 42 and 44, each of which is notched as indicated at 46 and 48. Cover portion 40 only is connected to the side wall 10 by means of a separating score line 50, sections 42 and 44 being completely cut away from the margin of the side wall 10 in the blank-forming die cut operation.

Beyond the ends of sections 16 and 16' and separated therefrom by score line 37 is a transverse partition section 52. This partition section is slotted from score line 37 delineating the margins of end sections 16 and 16', the slot being in alignment with score line 19 separating the sections to provide a narrow slotted portion 54 at the base of the partition and a somewhat wider slotted portion 56 extending outwardly to a point near the end of the partition section. The partition section 52 is slotted at its outer free end as indicated at 58. A score line 60 extends across section 52 in longitudinal alignment with score line 25 separating bottom section 18 from partition section 20. A partition section 52' identical in every respect with section 52 projects beyond the ends of the duplex end wall 14, 14' and is separated therefrom by score line 39.

Projecting beyond the other end of duplex side wall 16, 16' and separated therefrom by score line 41 is an end cover tab 62 divided into sections by a score line 64 aligned with score line 19 separating sections 16 and 16'. An identical end cover tab 66, similarly separated from the other end of duplex wall 14, 14', by score line 43 and extending therebeyond is divided into sections by score line 68.

The first step in setting up the carton from the blank illustrated in Fig. 1 and described above is illustrated in Fig. 2. The blank is folded along score lines 11, 13 and 17 and the adhesive-coated tab 18 is pressed against the inside of the free margin of side wall 12, thus setting up the side and end walls of the rectangular carton.

The next step illustrated in Fig. 3 involves folding the wings embodying bottom sections 18 and 18' and longitudinal partition sections 20 and 20' along score lines 23, 25, 27 and 29, respectively. The fold along score lines 23 and 27 is inwardly and outwardly along score lines 25 and 29. The partition sections 20 and 20', to one side of the latter of which adhesive has been applied as hitherto described, are then brought into face-to-face contact and the two partition sections are pressed together to form a single integral section extending upwardly from the longitudinal median line of the bottom of the carton. The bottom is formed by the two component sections 18 and 18', which sections are held in abutting relation by the integrated longitudinal partition formed of sections 20 and 20'.

Prior to folding inwardly the two wing sections as thus described to form the longitudinal partition and bottom of the carton, transverse partitions 52 and 52' are folded inwardly along score lines 37 and 39, positioning them within the four walls of the carton in juxtaposition

with the end walls, respectively, as clearly illustrated in Figs. 3 and 4. It should be noted that the distance between score lines 37 and 60 of transverse partition section 52, and correspondingly in conjunction with transverse partition section 52', is equal to a specific fraction of the length of the carton. For example, for purposes of illustration herein a ten-cell carton has been illustrated and the distance between score lines 37 and 60 is equal to one-fifth of the longitudinal dimension of the carton. The reason for this will appear hereinafter.

Referring now to Figs. 5 and 6, it will be seen that the next step in setting up the carton is 15 to fold the transverse partitions 52 and 52' along score lines 60 and 60' by pushing downwardly on their upper edges, respectively. Slot 56 in transverse partition 52, and the corresponding slot in partition 52', receive the integrated 20 longitudinal partition. The slots indicated at 58 in conjunction with transverse partition 52 and the corresponding slot in transverse partition 52' are then engaged with and firmly positioned by the integrated locking tongues of the longitudinal partition. It will be noted that the thickness of the bottom of the carton is doubled 25 at the base of each of the two cells at the respective ends of the carton by reason of this construction.

During the aforesaid operation of locating the transverse partitions 52 and 52', the top partition section, composed of cover portion 40 and partitions 42 and 44, is moved outwardly about score line 50 and partitions 42 and 44 are folded 30 down along score lines 33 and 35. After the transverse partitions 52, 52' are set, the composite unit 40, 42, 44 is swung inwardly about score line 50 and the notches 46 and 48 engaged 35 respectively in the notches at the upper portion 40 of the integrated longitudinal partition section, these notches being formed by aligned notches 26, 26' and 28, 28', respectively, of the constituent sections which make up the integrated longitudinal partition of the finished carton. Thus it will be seen that the portions 42 and 44 form transverse partitions delineating the adjacent central cells of each five-cell unit and cover portion 40 closes the upper end of these 45 two central cells.

End cover tabs 62 and 66 may be folded down 50 along score lines 41 and 43 and the cover 34 then folded down along score line 31, the tabs 36 and 38 being inserted inside the wall of the carton on opposite sides of cover portion 40 to close the 55 carton. The carton completely set up except for positioning end cover tabs 62 and 66 and swinging down the cover of the carton is clearly illustrated in Figs. 7 and 8, the completely closed carton being shown in perspective in Fig. 9 and sectionally in Fig. 10.

Where the end cover tabs 62 and 66 are utilized, it will be seen that these, when positioned and in conjunction with the cover portion 40 of the top partition section and the main cover 34, provide a double thickness of material over the entire top of the cellular carton. The bottom wall of the carton is reinforced by an extra thickness of material at the base of each pair of end cells, thus further strengthening and rigidifying the 60 carton.

When set up in the form illustrated in Fig. 3, the carton is readily collapsed into the position illustrated in Fig. 11 by exerting pressure transversely of the carton against the lower corners of 75 the side walls 10 and 12. Transverse partitions

52 and 52' should first be positioned as illustrated in Figs. 3 and 4 to lie adjacent the duplex end wall sections. When pressure is so exerted the integrated longitudinal partition moves upwardly, carrying the bottom sections 18, 18' inwardly around score lines 23 and 27 into face-to-face contact. The ends of the carton formed, respectively, by duplex sections 14, 14' and 16, 16' collapse, respectively, about score lines 15 and 19 and the transverse partitions 52 and 52' fold inwardly along end central partition-receiving slots and a score line 70 extending between the outer end of slot 56 and notch 58 in the outer margin of each partition 52, 52'. When the carton is flattened out in this fashion the end cover sections 62 and 66 fold along score lines 64 and 68 and the top partition section comprising 40, 42 and 44 lies flat against the main cover 34.

When the box is in the flattened out or collapsed condition shown in Fig. 11 and just described, the individual units are readily stacked for shipment and storage. In order to set a carton up it is only necessary to remove one from the stack, exert pressure against the extreme ends of the collapsed carton to straighten out the bottom and end walls, and move the transverse partitions 52 and 52' down into the operative position illustrated in Fig. 5 and described above. The carton is then loaded and the top partition section folded down, the end cover sections and main cover being folded down after loading of the carton has been completed.

As will have been noted from the foregoing description, the operation of setting the box up into flattened condition for storage is the essence of simplicity. Only the end tab 18 and one of the constituent units of the ultimately integrated transverse partition need be supplied with adhesive, and only two pressure operations at these adhesive-spotted locations, respectively, are required.

While I have described a carton comprised of ten cells, it will be apparent that the essence of the invention comprising a single blank having longitudinal and transverse partition sections extending away from the side walls of the blank is susceptible to various modifications wherein cartons providing any number of cells may be developed. The use of separate cell-forming assemblies is entirely eliminated, thus obviating a separate assembly of outside carton and interior cell-forming structures. The carton and its compartments can be made to any desirable dimensions, the practical limit being only by the size of available manufacturing equipment. The number of compartments that may be desired is limited only by the increasing complexity of the assembly operation.

While I have described sections 20 and 20' as "longitudinal" partition sections, it should be understood that, depending on the size and proportions of the article to be packaged, these partition sections may be flexibly connected by a score line to either the long or the short margins of the side walls and the other sections correspondingly rearranged.

Having described a preferred embodiment of the invention, various modifications lying within its scope will be apparent to those skilled in the art and for that reason I wish to limit myself only by the appended claims.

What I claim is:

1. A cellular carton comprising side walls, end walls collapsible outwardly along their vertical median line, a bottom wall collapsible inwardly along its longitudinal median line, a longitudinal

partition centrally disposed within the carton integral with said bottom wall and movable upwardly into the carton on collapsing of the bottom wall, said longitudinal partition including 5 notched locking tongues adjacent its ends, and transverse partition members flexibly connected, respectively, to the bottom margins of the end walls, each said partition being divided by a transverse fold line into a bottom reinforcing portion and a cell wall portion and being slotted outwardly from a point adjacent its connection with its respective end wall for reception of the longitudinal partition and slotted inwardly from its outer free margin to form between adjacent 10 ends of the respective slots a solid portion engageable in the notch of a locking tongue when the bottom reinforcing portion of the transverse partition member overlies the bottom and the cell wall portion is disposed normal thereto.

2. A cellular carton comprising side walls, end walls collapsible outwardly along their vertical median line, a bottom wall collapsible inwardly along its longitudinal median line, a longitudinal partition centrally disposed within the carton 15 integral with said bottom wall and movable upwardly into the carton on collapsing of the bottom wall, said longitudinal partition including notched locking tongues adjacent its ends, and transverse partition members flexibly connected, respectively, to the bottom margins of the end walls, each said partition being divided by a transverse fold line into a bottom reinforcing portion and a cell wall portion and being slotted outwardly from a point adjacent its connection 20 with its respective end wall for reception of the longitudinal partition and slotted inwardly from its outer free margin to form between adjacent ends of the respective slots a solid portion a margin of which is engageable in the notch of a locking tongue when the bottom reinforcing portion of the transverse partition member overlies the bottom and the cell wall portion is disposed normal thereto.

3. A cellular carton comprising side walls, end 25 walls collapsible outwardly along their vertical median line, a bottom wall collapsible inwardly along its longitudinal median line, a longitudinal partition centrally disposed within the carton integral with said bottom wall and movable upwardly into the carton on collapsing of the bottom wall, said longitudinal partition including 30 upwardly notched locking tongues adjacent its ends, and transverse partition members flexibly connected, respectively, to the bottom margins of the end walls, each said partition being divided by a transverse fold line into a bottom reinforcing portion and a cell wall portion and being slotted outwardly from a point adjacent its connection 35 with its respective end wall for reception of the longitudinal partition and slotted inwardly from its outer free margin to form between adjacent ends of the respective slots a solid portion the upper margin of which is engageable under the notch of a locking tongue 40 when the bottom reinforcing portion of the transverse partition member overlies the bottom and the cell wall portion is disposed normal thereto.

4. A cellular carton comprising side walls, end 45 walls collapsible outwardly along their vertical median line, a bottom wall collapsible inwardly along its longitudinal median line, a longitudinal partition centrally disposed within the carton integral with said bottom wall and movable upwardly into the carton on collapsing of the bottom

tom wall, said longitudinal partition including notched locking tongues adjacent its ends, and transverse partition members flexibly connected, respectively, to the bottom margins of the end walls, each said partition being divided by a transverse fold line into a bottom reinforcing portion and a cell wall portion and being slotted outwardly from a point adjacent its connection with its respective end wall for reception of the longitudinal partition and slotted inwardly from its outer free margin to form between adjacent ends of the respective slots a solid portion engageable in the notch of a locking tongue when the bottom reinforcing portion of the transverse partition member overlies the bottom and the cell wall portion is disposed normal thereto, and a top partition section connected to the top edge of one of said side walls, said top partition section embodying opposed marginally slotted trans-

5
10
15
verse partition sections, the slots in said sections being engageable with the longitudinal partition to form cells adjacent to said end cells.

HUBERT VELMAN BOLDING.
